US00D765687S

(12) **United States Design Patent** (10) **Patent No.:** **US D765,687 S**
(45) **Date of Patent:** **** Sep. 6, 2016**

(54) **DISPLAY SCREEN OR PORTION THEREOF WITH GRAPHICAL USER INTERFACE**

(71) Applicant: **Apple Inc.**, Cupertino, CA (US)

(72) Inventors: **Jay Christopher Capela**, Santa Cruz, CA (US); **Gary William Gehiere**, Santa Clara, CA (US); **Markus Hagele**, San Francisco, CA (US); **Alexander Charles MacLean**, San Jose, CA (US); **Parthiban Mohanraj**, Cupertino, CA (US); **Ryan Olshavsky**, San Jose, CA (US); **Matthew Todd Schomer**, Santa Cruz, CA (US); **Ian Oakley Smith**, Mountain View, CA (US); **Evan Torchin**, San Francisco, CA (US)

(73) Assignee: **Apple Inc.**, Cupertino, CA (US)

(**) Term: **14 Years**

(21) Appl. No.: **29/479,030**

(22) Filed: **Jan. 10, 2014**

(51) LOC (10) Cl. **14-04**

(52) U.S. Cl.

USPC **D14/486**

(58) **Field of Classification Search**

USPC **D14/485-495**
CPC **G06F 3/0482; G06F 3/04842; G06F 3/04817; G06F 3/048; G06F 17/211; G06F 17/212**

(57) **CLAIM**

The ornamental design for a display screen or portion thereof with graphical user interface, as shown and described.

DESCRIPTION

FIG. 1 is a front view of a display screen or portion thereof with graphical user interface showing our new design;

FIG. 2 is another embodiment thereof;

FIG. 3 is another embodiment thereof; and,

FIG. 4 is another embodiment thereof.

The outermost broken lines in the figures show a display screen or portion thereof, and form no part of the claimed design. The dot-dash broken lines in the figures and the areas within the dot-dash broken lines show portions of the graphical user interface that form no part of the claimed design.

1 Claim, 4 Drawing Sheets
